CLAIM

The ornamental design for a needle and syringe destructor, as shown and described.

DESCRIPTION

FIG. 1 is a front perspective view of a needle and syringe destructor embodying our new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

The bottom surface is substantially planar.

FIG. 5

FIG. 6
